UNITED STATES PATENT OFFICE.

LOUIS DUNKELBERG, OF BROOKLYN, NEW YORK.

DESIGN FOR A SPECTACLE TEMPLE.

Application filed May 14, 1926. Serial No. 17,720. Term of patent 14 years.

To all whom it may concern:

Be it known that I, LOUIS DUNKELBERG, a citizen of the United States of America, residing at Brooklyn, county of Kings, State of New York, have invented a new, original, and ornamental Design for Spectacle Temple, of which the following is a specification, reference being had to the accompanying drawing, forming part thereof.

The figure is a side elevation of a spectacle temple embodying the new design, the spectacle frame being shown in outline in dotted lines.

The solid black portions in the drawing represent opaque material and the portions shown in white or lightly shaded are of translucent material.

I claim:

The ornamental design for a spectacle temple as shown.

In witness whereof I have signed this specification this 13th day of May, 1926.

LOUIS DUNKELBERG.
